UNITED STATES PATENT OFFICE.

ALVAN D. BROCK, OF WASHINGTON, DISTRICT OF COLUMBIA.

MANUFACTURE OF COILED METALLIC PIPES.

SPECIFICATION forming part of Letters Patent No. 276,763, dated May 1, 1883.

Application filed December 23, 1882. (No model.)

To all whom it may concern:

Be it known that I, ALVAN D. BROCK, a citizen of the United States, residing at Washington, in the District of Columbia, have invented certain new and useful Improvements in the Manufacture of Coiled Metallic Pipes; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 Figure 1 of the drawings represents a rear elevation, and Fig. 2 a plan of a device by which my improvement may be carried out. Figs. 3, 4, 5, and 6 are details hereinafter referred to.

20 My invention relates to coiling metal pipes; and it consists in appliances and manipulations hereinafter stated and described.

Heretofore it has been difficult, if not impossible, to bend coupled lengths of pipe, as 25 gas-pipe, &c., for the reason that if bent while cold the pipe would break at the point where the screw-threads are cut. If heated, the expansion of the coupling causes a displacement of the screw-threads, and a good joint is therefore seldom obtained. I have devised a method 30 of coiling pipes, preferably without heating, which removes the objection.

It has heretofore been difficult to make helical or spiral coils, especially flat or "faked" 35 coils, with a space between the separate bends of the pipe for the passage of heat, &c., when such coils are used in steam-boilers and heaters. I have devised a method and appliances by which the distances between the bends may be 40 perfectly regulated and a superior coil produced.

I will proceed to describe a machine by which my process may be carried out.

45 A represents a suitable frame. B is a plate or disk, made to rotate at the desired speed by suitable driving mechanism, as the shaft C and a train of gears leading back to driving-pulley D.

E is a hub of the size which the innermost 50 bend of the coil is desired to be. Interchangeable hubs will be used to determine the size of the interior of coils.

G is a clamp, of suitable construction, to retain or bear against the pipe or coil. As many of these clamps may be used as may be found convenient, and they are movable on the face of plate B, so as to be inserted in holes b. 55

F is guide-pulley, against which the pipes are rested while being fed to the machine.

J is a strip of rubber or leather belting, or 60 it may be a chain of iron or other metal, which is to be wound in with the tubes in the process of bending or coiling, and is of such thickness as to give the desired spacing between the bends of the coil when the strip is removed. 65

H is the pipe or tube. This pipe is clamped on the disk or plate B, and when the plate is put in rotation the pipe is wound up about the hub E, the strip J being wound in with it. The pipe may be wound in flat fakes, as shown in 70 Fig. 2, or in a spiral, as at M, Fig. 6, or in a conical or other form.

It is obvious that the plate B may remain stationary, and the pipe be carried or coiled round the hub by suitable mechanism, or by 75 hand, without departing from the spirit of my invention.

I will now describe my method of coupling different lengths of threaded pipe together in the process of coiling. 80

When the pipe has been coiled nearly to the end of a section a mandrel, as K, is inserted in the end of that and the next section of pipe. This mandrel may have a collar, as k, around it, to prevent its passing too far into either 85 length or joint of pipe, and it should be a little longer than the threaded sleeve I. The two pipes having been coupled with the mandrel in the adjacent ends, the coiling is continued until the coupling has been passed for a short 90 distance, the mandrel serving to take the strain from the pipe and coupling. As soon as the coiling has passed a little distance beyond the coupling the bending is stopped, the pipes uncoupled, and the mandrel removed, when the 95 pipes are again coupled and the work proceeded with; or sections may be joined until the coil is complete, and all the mandrels removed afterward. The coupling I is preferably a right-and-left coupling, and the screw-threads 100 are cut on the pipes to correspond.

Instead of using the mandrel J, I have sometimes made use of a peculiar coupling-sleeve, L. This has the thread cut only on the middle

portion of its inside surface, as shown, the two ends projecting over the pipes beyond the part on which the screw-threads are cut. In either case the coupling-sleeve and the pipe within it do not bend much, if at all, and so much of the coil as forms the coupling does not form a true curve.

I do not herein claim the cold-bent coil produced by the method described, reserving the right to claim the same in a separate application.

What I claim is—

1. A device for coiling metal pipes, which consists essentially of a disk or plate on which the pipes rest, a clamp for holding the pipe upon the disk, and a flexible strip which is interposed between the bends of the pipe as the work progresses, substantially as described.

2. The improvement in the art or method of coiling pipe with spaces between the bends, which consists in the interposition of a spacing-strip during the process of bending, substantially as described.

3. The improvement in art or method of bending pipe in sections, which consists of a

principal and intermediate step or steps, the former consisting in winding the pipe in coils, and the latter in supporting the ends of the pipe-sections to be united, so as to take off the strain incident to the operation of coiling, substantially as set forth.

4. The improvement in the art or method of coiling pipes in sections, which consists essentially in the insertion of a mandrel in the ends of the pipes while bending, and afterward removing the mandrel from the coil, substantially as described.

5. The improvement in the art or method of coiling pipes in sections, which consists in winding the pipe in coils with an interposed flexible strip, and supporting the pipe within the coupling during the operation of coiling, substantially as described.

In testimony whereof I affix my signature in presence of two witnesses.

ALVAN D. BROCK.
